(57) **CLAIM**

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.
FIG. 1 shows a display screen or portion thereof with animated graphical user interface showing our new design; FIG. 2 shows a second image thereof; and, FIG. 3 shows a third image thereof.

The dashed broken lines illustrate a display screen or portion thereof, and form no part of the claimed design.

(Continued)

The appearance of the graphical user interface transitions sequentially between the images shown in FIGS. 1-3. The process or period in which one image transitions to another forms no part of the claimed design.
